UNITED STATES PATENT OFFICE.

JACOB RIFKIN, OF WILKES-BARRE, PENNSYLVANIA.

UNION-GARMENT.

1,386,950.

Specification of Letters Patent.

Patented Aug. 9, 1921.

Application filed May 6, 1920. Serial No. 379,281.

To all whom it may concern:

Be it known that I, JACOB RIFKIN, a citizen of the United States, residing in Wilkes-Barre, Luzerne county, Pennsylvania, have 5 invented new and useful Improvements in Union-Garments, of which the following is a specification.

This invention relates to an improvement in overall union suits or other one piece garments, comprising a combined blouse or 10 shirt, and trousers.

One object of my invention is to facilitate donning and removing such garments.

Loosely fitting as is the blouse or shirt 15 portion of the present style of garment as commonly manufactured, elderly persons and those inclined to stoutness have some difficulty in putting on the union overall, and more difficulty in removing the garment, due to the fact that it is necessary to 20 throw the shoulders back and toward each other in order to strip the shoulder portions of the garment off of the shoulders of the wearer.

Garments equipped with my invention 25 obviate this disadvantage, and are easily put on and taken off with a minimum of trouble and without loss of time.

The back and breast pieces of the usual 30 union overall are permanently connected or fastened together by shoulder seams extending in opposite directions along the top of the shoulder from the neck opening to the upper ends of the armscyes or arm holes, 35 and by seams extending from the armpits of the garment to the waist or belted portion.

The one piece collar of the garment is usually stitched to the edge of the material forming the neck opening, a slit or opening 40 extending down the front of the garment from and including the collar band to the crotch.

The spreading of this slit or opening, and the neck opening forms the aperture through 45 which the body of the wearer must pass in putting on and removing the garment, and is amply sufficient, except when drawing the garment over the shoulders or in extricating the shoulders from the garment.

Therefore, to render such operations easier, I provide the garment with slits, openings, or vents extending along the tops of the shoulders from the collar band to a point adjacent, but preferably not meeting, the 55 upper ends of the respective arm holes, such

vents extending across and opening through the collar or collar band.

Suitable fastenings of any convenient type may be used to hold the shoulder vents closed.

These vents, combined with the usual front slit or opening above-mentioned, permit the breast of the garment to be laid open or turned back, so that the blouse portion can be easily removed from the shoulders of the wearer when the shoulder vents and front slits are unfastened, and in putting on the garment, the front pieces are drawn together over the breast of the wearer, after the arms are inserted in the sleeves, the 60 edges of the front slit fastened together, and the shoulder vents closed by means of the fastenings provided therefor.

Reinforcing means is provided to 65 strengthen the vented shoulder portions of the garment.

In the accompanying drawings, which 70 illustrate one of a number of embodiments of my invention, Figure 1 is a front view of a union overall equipped with my invention, one of the vents being opened to better disclose the construction;

Fig. 2 is a three-quarters view of the upper portion of the garment; and

Fig. 3 is a detail perspective view of a 85 shoulder portion of the garment.

Referring to the drawings, the garment comprises leg portions 1, 1, connected at the waist to a blouse formed of a back piece 2 and front pieces 3, 3. The back may be of a 90 single piece or of two or more pieces sewed together.

The pieces forming the front and back are cut at 4, 4, to form a neck opening, and at 5, 5, to form arm holes or scyes, and sleeves 95 6, 6 are secured to the material around the arm holes 5 in the usual manner, the rear side edges of the respective front pieces 3, 3 being attached to the front side edges of the back piece 2 by the seams 7, running 100 from the arm pits downwardly toward the waistline.

Heretofore, the rear edge of each of the front pieces 3, 3 between the neck opening and arm hole has been secured to the corresponding front edge of the back piece 2 by a shoulder seam, but my invention contemplates the formation of a vent at this point along the top of each shoulder.

To this end, the rear edges of the front 110

pieces 3, 3, and the front edges of the back piece on each side of the neck opening are left free for a distance along the top of each shoulder of the garment toward the top of the arm hole, to form vents 8, 8 sufficient to enable the shoulders of the wearer to easily pass through without contortion.

Such vents may extend approximately one-half of the distance between the neck opening and the respective arm holes, 5 though this length may vary without departing from the scope of the invention.

A doubled reinforcing strip 9 extends along the whole length of each shoulder from the top of the arm hole 5 to the neck opening 4, the free edges of the reinforcing strip being firmly secured to the rear edge of its front piece 3 between the rear end of the neck opening thereof to the top of the arm hole 5. The rear edge of the front piece is indicated by the dotted line 3^a and is inserted between the doubled or folded reinforcing strip 9.

These reinforcing strips 9, in effect, form extensions on the rear edges of the front pieces 3, 3 and lap over the corresponding front edges of the back piece 2, which front edges may be reinforced by strips 10, 10 preferably secured to the under sides thereof.

Lines of cross stitching 11, 11 close the ends of the vents 8 at the desired points, and separable fastenings 12 on the reinforcing strips 9 and the front edges of the back piece 2 may be used to close the vents intermediate the ends thereof.

Those portions of the rear edges of the reinforcing strips 9 between the lines of cross stitching 11 and the arm holes 5 are permanently secured to the adjacent front edges of the back piece 2 by stitching 11^a.

Because of the vents 8, 8, it is desirable to provide a sectional collar or collar band, projecting upwardly from the respective front and back pieces along the edge of the neck opening. I have illustrated such a band made in three pieces, one of which, 13, is attached to that edge of the back piece 2 forming the neck opening 4, the remaining sections 14, 14 being secured to the edges of the front pieces 3, 3 where they are cut at 4, to form the neck opening.

The rear ends of the collar sections 14, 14 of the front pieces 3, 3, extend across the width of the respective reinforcing strips 9, whereby to form extensions to overlap the front ends of the back collar sections 13, releasable fastenings 15 of any suitable kind, operating to connect the adjacent ends of the collar sections.

By the use of the fastenings 15, it might be possible to eliminate the fastenings 12.

Obviously, the reinforcing strips 9 might be applied to the front edges of the back piece 2 to overlap the rear edges of the front

pieces 3, 3, in which case, the reinforcing strips 10 would be secured to the rear edges of the respective front pieces.

The opening between the adjacent front edges of the front breast pieces 3, 3 is provided with buttons and button holes 16 or other convenient releasable fastenings whereby the opening may be held closed.

Changes may be made in the form and arrangement of the several parts described without departing from the spirit and scope of my invention.

What I claim as new, is:—

1. The combination in a blouse or shirt comprising a back piece and front pieces and having armholes and a neck opening; of reinforcing strips connected to the rear edges of the respective front pieces between the neck opening and the armholes, to form extensions of the front pieces and overlap the corresponding front edges of the back piece; stitching to connect the overlapping portions of the reinforcing strips to the adjacent front edge of the back piece, from the armholes to points partway toward the neck opening to form shoulder vents; a sectional collar or collar band, one section of which is connected to the back piece at the neck opening, and the remaining sections being secured to the respective front pieces at the neck opening; and means to releasably close the vents.

2. The combination in a blouse or shirt comprising a back piece and front pieces and having armholes and a neck opening; of reinforcing strips connected to the rear edges of the respective front pieces between the neck opening and the armholes, to form extensions of the front pieces and overlap the corresponding front edges of the back piece; stitching to connect the overlapping portions of the reinforcing strips to the adjacent front edge of the back piece, from the armholes to points partway toward the neck opening to form shoulder vents; a sectional collar or collar band, one section of which is connected to the back piece at the neck opening, and the remaining sections being secured to the respective front pieces at the neck opening; the rear ends of the respective front collar sections extending across and secured to the ends of the reinforcing strips adjacent the neck opening to form extensions which overlap the front ends of the rear collar section; and means to releasably connect the overlapping portions of the collar sections.

3. The combination in a blouse or shirt comprising a back piece and front pieces and having armholes and a neck opening; of folded reinforcing strips embracing the rear edges of the respective front pieces between the armholes and neck opening, the reinforcing strips serving as extensions of the front pieces to overlap adjacent por-

- tions of the front edge of the back piece; a portion of each reinforcing strip from the armhole partway only to the neck opening, being secured to the overlapped edge of the 5 back piece, to form shoulder vents; collar sections secured to the respective front and back pieces at the neck opening; and means to releasably connect the front ends of the rear collar section with the rear ends of the 10 respective front collar sections.
4. The combination in a blouse or shirt, comprising a back and front pieces and having arm holes and a neck opening; of folded reinforcing strips embracing the rear edges 15 of the respective front pieces between the armholes and neck opening, the reinforcing strips serving as extensions of the front pieces to overlap the adjacent portions of the front edge of the back piece; a portion of each reinforcing strip from the armhole 20 partway only to the neck opening, being secured to the overlapped edge of the back piece, to form shoulder vents; cross stitching to connect the reinforcing strips intermediate their ends with the back piece, to 25 close one end of each vent; and collar sections secured to the respective front and back pieces at the neck opening.

JACOB RIFKIN.
